DESIGN FOR A NOVELTY DOLL

Vivian Bennett, Chicago, Ill., assignor to McLaughlin & Wallenstein, Chicago, Ill.

Application September 30, 1939, Serial No. 87,448

Term of patent 7 years

To all whom it may concern:

Be it known that I, Vivian Bennett, a citizen of the United States, residing at Chicago, in the county of Cook and State of Illinois, have invented a new, original, and ornamental Design for a Novelty Doll, of which the following is a specification, reference being had to the accompanying drawings, forming a part thereof.

Fig. 1 is a perspective view of a novelty doll, showing my new design; and

Fig. 2 is a similar perspective view taken from an angle approximately opposite to that of Fig. 1.

The drawings are lined to indicate contrasting color.

I claim:

The ornamental design for a novelty doll, as shown and described.

VIVIAN BENNETT.
